UNITED STATES PATENT OFFICE.

HANS HOLZWARTH, OF MANNHEIM, GERMANY, ASSIGNOR OF ONE-HALF TO ERHARD JUNGHANS, OF SCHRAMBERG, GERMANY.

GAS-TURBINE.

1,113,347.

Specification of Letters Patent. Patented Oct. 13, 1914.

Application filed September 28, 1909. Serial No. 518,213.

To all whom it may concern:

Be it known that I, HANS HOLZWARTH, a subject of the German Emperor, residing at Mannheim, in the Empire of Germany, have invented certain new and useful Improvements in Gas-Turbines, of which the following is a specification:

This invention relates to an improved arrangement for regulating gas turbines which are driven by the periodic explosion of a combustible mixture in a number of so called combustion chambers grouped about the rotor and more particularly to that type of turbine in which these combustion chambers are first scavenged with air after the firing of a charge whereby they become cooled and filled with air, and then a supply of combustible is admitted into the air filled chamber which finally, after suitable mixing, is exploded with the air.

In the turbine of the present invention each combustion chamber is provided with regulating valves for air, combustible and for the products of combustion. The main regulating of the turbine is effected by cutting out, that is to say entirely suspending the explosion in one or more of the explosion chambers grouped around the rotor and a finer degree of control is possible by regulating the degree of opening of the air and gas inlet valves, and by varying the proportions of air and gas to obtain a varying strength of mixture. This regulation may be automatically controlled by a servomotor or the like.

The exhaust valve of the combustion chambers is arranged as a nozzle valve between the combustion chamber and the turbine itself. This valve is for the purposes of the present invention closed during the formation of the explosive mixture in the combustion chamber to prevent the escape of any unburnt combustible, and is arranged to be opened automatically by the explosion. It is then subsequently prevented by a special means from closing again for a sufficient time after the air inlet valve of the combustion chamber has been opened to allow sufficient air to flow in behind the products of combustion which obtains a thorough scavenging of the combustion chamber and also acts to sufficiently cool this latter and the turbine itself. The nozzle valve is then closed and combustible

is admitted through its inlet valve. The nozzle valve may be again opened for a short while in order that the unmixed air near it can be expelled so that the mixture is a uniform one in the combustion chamber prior to ignition.

The arrangement whereby the valves are simultaneously automatically controlled, for instance, by a servomotor or the like, is more particularly described below.

The present invention is more particularly described with reference to the accompanying drawings which are however to be merely regarded as diagrammatic examples of construction.

Figure 1 is a diagrammatic view of a turbine showing the various valves applied to the combustion chambers. Fig. 2 is a sectional view of an inlet valve. Fig. 3 is an outside elevation partly in section of a means for controlling the degree of opening of the inlet valve shown in Fig. 2. Fig. 4 shows an alternative construction of inlet valve. Fig. 5 illustrates by way of example a form of servomotor directly controlling the throttle valve for the gas supply.

Referring to Fig. 1, 8 is the combustion chamber provided with the so called nozzle valve 10 adapted to close the passage 9 leading to the nozzle. The nozzle valve 10 is pressed on its seat by means of a spring 17 acting on a collar on the valve spindle 98. This valve spindle is provided with a stop 20 formed for instance with a central slot 99 in which the roller 99 of a lever 21 lies. The lever 21 is connected by means of a rod 23 with a rocking lever 74 having a roller 55 or the like at one end adapted to be operated by a cam 25 on the valve shaft 27. As the distance between the valve shaft 27 controlling the period of opening of the exhaust valve 10 and the stop 20 of the valve spindle 98, is such that a rod of considerable length is required, it is necessary in order to obtain smoothness of action, to arrange that the controlling rod 23 should constantly follow the automatic movements of the stop 20, when for instance the valve is suddenly thrust upward by an explosion. For this purpose the spring 22 is used, connected as shown in the manner illustrated in the drawings. The valve 10 is opened by the explosion pressure and then immediately afterward the cam 25 passes beneath the roller 55.

2

55 so that the roller 99 arranged at the other end of the system of rods 74, 23, 21, is held up in the catch 20 and prevents the valve 10 from again closing until the operating 5 chamber 8 is sufficiently evacuated and scavenged with air. Valves 28, 50 are arranged in each combustion chamber for the purpose of admitting air and combustible respectively into the combustion chamber 8. 10 These valves are controlled from the valve shaft 27 which for this purpose carries cams 26, 96 which act on levers 24, 84, respectively and which by means of rollers 19, 85, press on the spindles of these inlet valves 28, 50. 15 Special means are provided for controlling the amount of opening of these inlet valves. In one example of construction, as illustrated in Fig. 2, the head of the valve stem 18 carries a ring 52 which has a screw 20 threaded surface. With this engages a correspondingly internally threaded cap 30. This cap 30 carries an arm 53 which is connected by ball and socket joint to a lever arm 32 connected with a piston 31 in a cylinder 54 which is in communication by means of a pipe A with a source of oil or like medium under pressure, the flow of which to the cylinder 54 is controlled by a servomotor. The valve 28 is opened by a 25 cam 26 on the valve shaft 27 which acts upon a roller 56 at one end of a lever 24 so that the roller 19 at the opposite end of the lever 24 acts to depress the cap 30 and open the valve. It will be seen that the amount 30 of opening of the valve will depend upon the amount of displacement of the piston 31 in the cylinder 54. The cap 30 upon the screw threaded head 52 of the valve stem 18 is so adjusted that it may be displaced along 35 the part 52 to the full movement of the roller 19 in such a manner that when the piston 31 is displaced to its full extent to shorten the effective length of the valve stem, the valve 28 will not be opened at all when the 40 cam 26 acts to lift the roller 56, but the valve will be fully opened when the piston is displaced in the opposite direction to make the valve stem of a greater effective length. It will be seen therefore that by controlling 45 the position of the cap 30 relatively to the valve spindle 18, any desired length of valve spindle may be obtained. The displacement of the cap 30 relatively to the valve spindle 18 is generally effected by 50 fluid pressure, but it is obvious that it can be effected by a direct connection. For instance it may be rotated by pinion gearing or in any other desired manner. The valve 55 illustrated in detail in Fig. 4, and which 60 may be seen on the right of Fig. 1, is in the construction illustrated of similar form to the valve 28. It is to be pointed out that in the present description for the purpose of clearness, the controlling mechanism as 65 shown in Fig. 2 is described with reference

to the air valve 28, while an alternative form of control as shown in Fig. 4, is described with reference to the combustible valve 50, but these controls are alternatives and can be applied to either the air valve or the combustible valve as desired.

Referring to Fig. 4 it will be seen that the valve spindle 60 carries at its end a cylinder 61 in which slides a piston 91. This piston is carried by a piston rod 62 which is hollow. A pipe 63 leads to the source of fluid pressure controlled by the servomotor. The oil or like medium under pressure may pass through the perforation 64 in the spindle 62 and along the passage 65 to enter the cylinder. It will be seen that the effective volume of the cylinder can be altered at will and thereby the lift or degree of opening of the valve 50 by the operating cam 96 on the valve shaft 27, can be adjusted in an equivalent manner to the control described with reference to Fig. 2. The air inlet valve 28 as may be seen from Fig. 1, is in communication with the main air inlet passage 100, while the gas inlet valve 50 is in communication with the main gas inlet passage 101. In certain cases to obtain a particular control, the main supply of gas may be regulated, which regulation however is independent of the secondary gas regulation effected by varying the lift or degree of opening of the gas inlet valve. This primary throttling of the gas supplied to the main gas passage 101 which it will be seen effects the supply of gas to all the valves communicating with the gas passage 101, is obtained by means of a valve 36 (Fig. 5) the degree of opening of which can be adjusted by the corresponding displacement of a piston 34 in a cylinder 102, in the example shown by oil pressure from the servomotor.

In the example shown in Fig. 5 a servomotor is adapted to control all the automatic hydraulically operated parts. The operation of the servo-motor is controlled by the governor (not shown) through the rod 65 which is connected by a link 105 to a connecting rod 104 connected to the controlling piston 103. The movement of the piston 103 allows the pressure medium, such as oil under pressure, to flow to either one or the other side of the piston 34 raising or lowering the valve 36 and also the multiple valve 108 which controls the flow of pressure oil through a series of passages to a number of chambers 109 connected by pipes to respective valves and like parts to be operated automatically. Supposing, for instance, the lever 35 be depressed about the pivotal center 110 which is on a rod 111 connected to the piston 34, then the valve 103 will be moved to allow fluid to pass to the underside of the piston 34 which will raise the valve 36, simultaneously cause the movement of the valve 108 and consequent opera-

tion of the parts controlled thereby. The upward motion of the piston 34 with its rod 111 will raise this latter with the pivotal point 110 of the lever connected to the rod 35. The point 112 will then act as the center of rotation for the links and the connecting rod will be raised to cause the valve 103 to cut off again so that the piston 34 comes to a standstill at the desired adjusted position.

10 It is to be understood that the constructions of valve control, servomotor, and other controlling parts are described above by way of reference only and it is obvious that other suitable equivalent means may be used to effect the same purpose. In the example shown in which oil pressure is the controlling medium acting through the servomotor there is the advantage that should the oil pressure which is indispensable for the entire operation, cease for any reason whereby the bearings fed from the same source of oil would be greatly endangered, then all the valves controlled by the valve pressure would momentarily be closed owing to the absence of pressure, and consequently the turbine is slowed down or stopped.

15

The action of the turbine is as follows: Consider ignition to have taken place in one of the explosion chambers 8, then the shock of the explosion will lift the exhaust nozzle valve 10 and move its valve spindle 98 with the stop 20 upward against the action of the spring 17; the cam 25 will then immediately pass beneath the roller 55 so that the roller 99 on the outer end of the system of rods 74, 23, 21 is held up in the catch 20 whereby the valve 10 is prevented from again closing under action of the spring 17 until the combustion chamber 8 is sufficiently evacuated and scavenged with air which will now be passing through the valve 28 opened by the cam 26. The cam 25 will now allow the valve 10 to shut off the combustion chamber from the turbine and then by means of a further cam 96 the gas inlet valve 50 will be opened. The closing of the air valve 28 may take place shortly before the opening of the gas inlet valve. The mixing of the gases with the air contained in the explosion chamber 8 now takes place. This process of mixing is very substantially accelerated and improved in that the exhaust valve 10 is now opened momentarily, preferably during the last part of the period of admission of the gas, by means of the cam 40 on the valve shaft 27 acting on the roller 55. This re-opening of the exhaust valve 10 allows the air in the neighborhood of the valve which has not yet been mixed with the gas to be expelled, but the time of opening is so short that no un-burnt combustible can escape. After this valve 10 has again been closed a second time ignition will take place. The ignition apparatus

has not been illustrated but can be suitably operated by means of a cam on the controlling shaft 27. The pressure of the products of combustion now forces open the valve 10 so that the gases flow into the turbine to perform useful work there. The cycle of operations described above begins again and once more the valve 10 will be held open long enough for sufficient air for cooling and so on.

75 As has already been stated the turbine is controlled primarily by a so-called pause control, that is to say, the firing in one or more of the combustion chambers is interrupted, and secondly the amount of opening 80 of the inlet valves both air and gas, can be regulated in the manner described above, and thirdly it is possible to alter the strength of mixture by opening the gas throttle valve 36 to a greater or less degree. 85 This gas throttling control is necessary as it will be seen that when the succession of explosions is accelerated the duration of the period of gas admission into the air filled combustion chambers will correspondingly be shortened and less gas would enter the combustion chambers than before. That is to say the mixture would become poor. This weakening of the mixture would not only tend to counteract the intended regulation but would also act to diminish the efficiency of the turbine because the pressure developed by the explosions would no longer correspond to the dimensions of the nozzles. The throttle valve is therefore arranged to be controlled so that the strength of mixture is always a correct one to obtain an efficient operation of the turbine at any given speed. This throttling allows the pressure of the gas introduced into the main 100 gas passage to be suitably increased when the explosions take place in more rapid succession, and to be suitably diminished when the succession of explosions is slower. Also of course the gas inlet valves to the 105 combustion chambers could be held open considerably longer in the case of more rapid succession. In the primary regulation by cutting out one or more of the explosion chambers the air supply will be shut off 110 synchronously with the shutting off of the gas supply to a chamber, whereby a very considerable economy in compression work is obtained. Further in the event of a sudden strong relieving of the load for instance 115 by a short circuit of the dynamo which is being driven by the gas turbine or by any other like cause, the introduction of the air and the gas will be gradually shut off to obtain a very safe regulation.

120 I declare that what I claim is:

1. A gas turbine consisting of a rotor, a combustion chamber, means for leading the products of combustion to said rotor, valves for air and combustible in the com- 130

bustion chamber, controlling gear for the said valves, a valve in the chamber for the products of combustion, adapted to be opened by the pressure of the exploded 5 gases and means for holding it open for the requisite time.

2. A gas turbine consisting of a rotor, a combustion chamber, means for leading the products of combustion to said rotor, valves 10 for air and combustible in the combustion chamber, controlling gear for the said valves, a valve in the chamber for the products of combustion, adapted to be opened by the pressure of the exploded gases, means 15 for holding open the said valve for the necessary time, and means for opening the said valve a second time.

3. A gas turbine consisting of a rotor, a combustion chamber, means for leading the 20 products of combustion to said rotor, valves for air and combustible in the combustion chamber, controlling gear for the said valves, a valve in the chamber for the products of combustion, adapted to be opened by 25 the pressure of the exploded gases, means for holding open said spring loaded valve for the necessary time, a rotary controlling shaft and means provided on the said shaft for opening the said valve a second time.

4. A gas turbine consisting of a rotor, a combustion chamber, means for leading the products of combustion to said rotor, valves for air and combustible in the combustion chamber, controlling gear for the said 35 valves, a spring loaded valve in the chamber for the products of combustion, adapted to be opened by the pressure of the exploded gases, means for positively holding it open for the requisite time, and positive means 40 for forcing open the valve a second time.

5. A gas turbine consisting of a rotor, a combustion chamber, means for leading the products of combustion to said rotor, valves for air and combustible in the combustion 45 chamber, controlling gear for the said valves, a member of variable length between said valves and said controlling gear, a valve in the chamber for the products of combustion, adapted to be opened by the 50 pressure of the exploded gases and means for holding it open for the requisite time.

6. A gas turbine consisting of a rotor, a combustion chamber, means for leading the products of combustion to said rotor, valves 55 for air and combustible in the combustion

chamber, controlling gear for the said valves, a member of variable length between said valves and said controlling gear, hydraulically operated means for varying the length of said member, a spring loaded 60 valve in the chamber for the products of combustion, adapted to be opened by the pressure of the exploded gases and means for holding it open for the requisite time.

7. A gas turbine consisting of a rotor, a combustion chamber, means for leading the products of combustion to said rotor, valves for air and combustible in the combustion chamber, controlling gear for the said valves, a member of variable length between said 65 valves and said controlling gear, hydraulically operated means for varying the length of said member, a distributor under the action of the governor of the turbine for controlling the said hydraulically operated 70 means, a spring loaded valve in the chamber for the products of combustion, adapted to be opened by the pressure of the exploded gases and means for holding it open for the requisite time.

8. A gas turbine consisting of a rotor, a combustion chamber, means for leading the products of combustion to said rotor, automatically closing valves for air and combustible in the combustion chamber, gear for 85 opening the said valves, means for disconnecting said gear and valves when the movement of the said gear is interrupted, a valve in the chamber for the products of combustion, adapted to be opened by the pressure of the exploded gases, and means for holding it open for the requisite time.

9. A gas turbine consisting of a rotor, a plurality of combustion chambers, means for leading the products of combustion to the 90 said rotor, valves for air and combustible in each combustion chamber, controlling gear for the said valves, a valve in each chamber for the products of combustion, adapted to be opened by the pressure of the 100 exploded gases and means for holding it open for the required time.

In witness whereof, I have hereunto signed my name this 11 day of September 1909, in the presence of two subscribing witnesses.

HANS HOLZWARTH.
